K. A. OLSON.

APPARATUS FOR RAISING SUNKEN VESSELS AND THE LIKE.

APPLICATION FILED JULY 23, 1918.

1,308,528.

Patented July 1, 1919.

FIG. 1.

FIG. 2.

FIG. 4.

FIG. 3.

4 Inventor

Karl A. Olson,

By his Attorneys

Edgar V. Allen

UNITED STATES PATENT OFFICE.

KARL A. OLSON, OF PLAINFIELD, NEW JERSEY.

APPARATUS FOR RAISING SUNKEN VESSELS AND THE LIKE.

1,308,528.

Specification of Letters Patent.

Patented July 1, 1919.

Application filed July 23, 1918. Serial No. 246,339.

To all whom it may concern:

Be it known that I, KARL A. OLSON, a citizen of the United States, and residing at Plainfield, in the county of Union and 5 State of New Jersey, have invented certain new and useful Improvements in Apparatus for Raising Sunken Vessels and the like, of which the following is a specification, such as will enable those skilled in the art to 10 which it appertains to make and use the same.

This invention relates to apparatus for raising sunken vessels and particularly to apparatus of this class employing pontoons 15 which are connected with the sides of the hull, and the object of my invention is to provide improved means for attaching the pontoons to the hull of a vessel; and a further object being to provide means for equalizing the lifting power of each pontoon 20 through a plurality of connections with the hull; and with these and other objects in view the invention consists in an apparatus of the class and for the purpose specified, 25 constructed and operating as hereinafter described and claimed.

The invention is fully disclosed in the following specification, of which the accompanying drawing forms a part, in which the 30 accompanying drawing forms a part, in which the separate parts of my improvement are designated by suitable reference characters in each of the views, and in which:—

Figure 1 is a side view of a portion of a hull of a vessel showing two pontoons connected therewith;

Fig. 2 a partial section on the line 2—2 of Fig. 1;

Fig. 3 a partial section on the line 3—3 of Fig. 1 and on an enlarged scale, and

40 Fig. 4 a partial section on the line 4—4 of Fig. 3.

In the drawing, I have indicated at 10 the hull of a vessel and when it is desired to raise a sunken vessel, a plurality of bolt-like attachments 11 are connected with the hull at spaced intervals as indicated in Fig. 1, said attachments comprising a threaded shank portion 12 which passes into and through the hull, a central collar 13, a reduced neck portion 14 and a tapered head portion 15.

The attaching devices 11 may be connected with the hull in any desired manner but are preferably connected by means of the diving bell construction shown in my prior application Serial No. 230,221, filed Apr. 28, 1918.

In Figs. 1 and 2, I have shown at 16 a pontoon or pontoons of the usual or any desired form and construction and, in the practice of my invention, I provide the opposite end portions of the pontoon with straps 17 in the lower ends of which are mounted pulleys 18 over and around which pass a cable 19 to the ends of which are secured couplings 20. The couplings 20 consist of upwardly directed hollow conical heads 21 which form sockets for the ends of the cables 19 and downwardly directed yoke-shaped head portions 22 provided with a large central aperture 23 and a smaller arc-shaped aperture 24 which is adapted to receive the reduced neck portion 14 of the attaching device 11 as clearly shown in Fig. 4.

The downwardly directed yoke-shaped portions 14 of the couplings 20 are provided 75 at the opposite sides thereof with outwardly directed lugs 25 which are inclined downwardly and inwardly. Suspended from the cable 19 between the pulleys 18 of each pontoon 16 is a pulley device 26 carrying a cable 80 27 to the lower end of which is connected a coupling 20 similar in all respects to the couplings 20 secured to the ends of the cables 19.

The above construction forms an equalizing mechanism for the pontoons which will equalize the lifting power of the cables 19 and 27 to each of the couplings 20 regardless of the position or location of the attaching devices 11 in the hull, and this is clearly 90 illustrated at the left of Fig. 1 of the drawing.

It will be understood that the pontoons may be connected with the attaching devices 95 11 secured to the hull in any desired manner or with any suitable apparatus, and when the required number of pontoons have been connected with the hull the water or other substance therein is pumped out in the usual or any desired manner and the vessel may be 100 raised, but as above stated, my invention is not limited to the form, construction and operation of the pontoons, and for this reason the detail construction thereof has not been shown nor described, the only essential 105 feature being the equalizing mechanism employed, and while I have shown a specific construction for carrying my invention into effect, I am not limited to the details of this construction, and changes therein and modifications thereof may be made, within the 110 scope of the appended claims, without de-

parting from the spirit of my invention or sacrificing its advantages.

Having fully described my invention, what I claim as new and desire to secure by 5 Letters Patent, is:—

1. In an apparatus for raising sunken vessels, a plurality of pontoons, an equalizing mechanism for said pontoons comprising a plurality of pulleys suspended beneath each 10 pontoon, a cable passed over and around said pulleys, couplings connected with the ends of said cable, a pulley device mounted on and movable longitudinally of said cable between said first named pulleys, a cable suspended from said last named pulley device and a coupling connected with said last 15 named cable.
2. In an apparatus for raising sunken ves-

sels, a plurality of pontoons, an equalizing mechanism for said pontoons comprising two 20 pulleys connected with each pontoon, a cable passed over and around said pulleys, coupling members connected with the free ends of said cable, another pulley mounted on and movable longitudinally of said cable between said first named pulleys, and a coupling suspended from said last named pulley.

In testimony that I claim the foregoing as my invention I have signed my name in 30 presence of the subscribing witnesses this 20th day of July, 1918.

KARL A. OLSON.

Witnesses:

C. E. MULREANY,
H. E. THOMPSON.
